UNITED STATES PATENT OFFICE

EDWIN B. DONALDSON AND WILLIAM W. DONALDSON, OF WASHINGTON, DISTRICT OF COLUMBIA

BARRICADE

Application filed March 5, 1931. Serial No. 520,388.

This invention relates to barricades such as are generally used by contractors in road constructions, excavations and the like, and it is primarily an object of the invention to provide a device of this kind which, when not in use, may be folded or compacted to occupy a minimum of space and which, when extended for use, is so arranged as to effectively maintain itself in proper placement and particularly to withstand the wind.

An additional object of the invention is to provide a device of this kind comprising a standard having associated therewith bracing members, said bracing members being capable of adjustment into different positions as the occasions of practice may require and wherein means are provided for effectively maintaining said bracing members in desired position with respect to the standard.

The invention also has for an object to provide a device of this kind with means whereby a horizontally disposed board or kindred member may be readily comprised in the barricade when so desired.

The invention consists in the details of construction and in the combination and arrangement of the several parts of our improved barricade whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a view in perspective illustrating a barricade constructed in accordance with an embodiment of our invention;

Figure 2 is a fragmentary view in perspective of the upper portion of the device as illustrated in Figure 1 showing the bracing members disposed in opposite directions;

Figure 3 is a view in perspective of the device in compacted or folded adjustment;

Figure 4 is a view in top plan of the device as illustrated in Figure 3, the bottom

cross member for the standard being omitted;

Figure 5 is a view in perspective illustrating a plurality of our improved barricades in assembled relation;

Figure 6 is an enlarged fragmentary view in perspective illustrating an attachment for use in connection with a barricade.

As herein disclosed, our improved barricade comprises a standard 1 of desired length and stability and which is provided at its bottom extremity with a cross member 2. This cross member 2 extends a material distance beyond the opposite sides of the standard 1 and is at right angles thereto and acts as a means to assure the desired maintenance of the upright or standard 1 in working position. The lower edge of this cross member 2 is substantially flush with the adjacent or bottom end face of the standard 1.

The upper end portion of the standard 1 has suitably anchored or affixed thereto a plate 3 having its central portion extending beyond the opposite side faces of the standard 1 and with the upper and lower portions of each side margin of the plate 3 disposed on an inward incline, as at 4, said inclines having their lower points outwardly disposed and providing effective cam surfaces for a purpose to be hereinafter more particularly referred to.

Disposed through the upper portion of the standard 1 is a bolt or kindred headed member 5 having associated therewith a conventional nut 6. This bolt or member 5 is of a length to project a material distance beyond the opposite side faces of the standard 1 and said extremities are also freely disposed through end portions of the brace members 7. These members 7 are of desired length as may be best determined by the requirements of practice.

The headed member or bolt 5 is positioned at a point substantially midway of the ends of the plate 4 so that when the brace members 7 are swung into extended position they will pass over certain of the cam surfaces 4 with the result that the brace members 7 are effectively maintained in their desired extended or working position. In Figure 1

these members 7 are shown as disposed in the same general direction and it will be noted that the resultant coaction with the plate 3 maintains these brace members 7 in divergence with respect to the standard 1 so that when the device in its entirety is placed upon the desired supporting surface an effective barricade is provided and one which will readily withstand the action of the wind.

10 When the device is not in use the brace members 7 may be readily folded to lie lengthwise along the opposite sides of the standard 1 as illustrated in Figure 3 so that the device in such condition will occupy a minimum of space which is particularly desirable both in transportation and in storage.

15 As particularly illustrated in Figures 2, 4 and 5, the brace members 7 may be disposed in opposite directions with respect to the standard 1 when the device is in use and by having a brace 7 of one barricade crossing the adjacent brace of a succeeding barricade and substantially in contact an elongated barricade assembly may be obtained which will readily maintain itself in desired placement and which will also effectively withstand the force of the average wind velocity. In this particular assembly it is to be observed that the second brace member 7 20 of the barricade closely approaches the cross member 2 of the succeeding barricade.

25 If desired to further support the assembly as illustrated in Figure 5, a barricade in the adjustment as illustrated in Figure 1 may be placed against the elongated assembly at desired points therealong and in lateral relation thereto.

30 We also find it of particular advantage under certain conditions to employ in connection with our improved barricades the attachment as illustrated in Figure 8 and which attachment comprises a plate 8 provided at its extremities and at opposite sides thereof with the upstanding arms or lugs 9 and at its central portion with depending arms or lugs 10.

35 The plate 8 is adapted to be rested upon the upper end face of an upright 1 with the arms or lugs 10 extending along opposite faces thereof. When the attachment is applied a horizontal board, beam or the like may be rested upon the plate to extend in the same general direction as the brace members 7 or at substantially right angles thereto. This attachment is particularly advantageous for use in closing the entrance to a highway and under which condition it is generally only required that two of our improved barricades be used with a board or plank connecting said barricades and operatively engaged with the applied attachments. If desired, a relatively long continuous barricade may be arranged by having the devices as illustrated in Figure 1 positioned at de-

sired intervals and connected by horizontally disposed boards or the like.

40 It is also possible with the use of our improved barricade when desired to swing one of the brace members or supports 7 in substantially a horizontal position with the outer or free end portion of such brace or supporting member operatively engaged with a second barricade or more particularly with an applied attachment.

45 From the foregoing description it is thought to be obvious that a barricade constructed in accordance with our invention is particularly well adapted for use by reason of the convenience and facility with which it may be assembled and operated, and it will also be obvious that our invention is susceptible of some change and modification without departing from the principles and spirit thereof and for this reason we do not 50 wish to be understood as limiting ourselves to the precise arrangement and formation of the several parts herein shown in carrying out our invention in practice except as hereinafter claimed.

55 We claim:—

1. A barricade comprising a stable upright, bracing members, means for pivotally connecting said bracing members to an end portion of the upright, said bracing members being movable to extend either fore or aft of the upright or to be placed in collapsed position alongside the upright.

60 2. A barricade comprising an upright, bracing members, means for pivotally connecting said bracing members to an end portion of the upright, said bracing members being movable to extend either fore or aft of the upright or to be placed alongside the upright in collapsed position, and a cross member carried by the bottom extremity of the upright and coacting with said members when extended in maintaining the upright in substantially vertical position.

65 3. A barricade comprising an upright, bracing members, means for pivotally connecting said bracing members to an end portion of the upright, said bracing members being movable to extend either fore or aft of the upright or to be placed alongside the upright, and means carried by the upright for holding the bracing members in their various extended positions.

70 4. A barricade comprising an upright, bracing members, means for pivotally connecting said bracing members to an end portion of the upright, said bracing members being movable to extend either fore or aft of the upright or to be placed alongside the upright, said bracing members being also movable to extend one on each side of the upright, and frictional means coacting with the upright and the bracing members for holding the bracing members in their various extended positions.

5. A barricade comprising an upright, bracing members, means for pivotally connecting said bracing members to an end portion of the upright, said bracing members being movable to extend either fore or aft of the upright or to be placed alongside the upright, said bracing members being also movable to extend one on each side of the upright, oppositely disposed cam surfaces extending beyond the side faces of the upright and with which the bracing members coact to maintain the bracing members in their various extended positions.

6. An attachment for the vertical standard of a barricade comprising a plate, means to secure the same to the standard, and upstanding brace arms pivotally carried by the standard and frictionally contacting with opposing edges of the plate, said plate acting to tension said arms upon movement of said arms into extended position with respect to said standard.

In testimony whereof we affix our signatures.

25 EDWIN B. DONALDSON.
WILLIAM W. DONALDSON.
